UNITED STATES PATENT OFFICE.

CHARLES J. VAN DEPOELE, OF CHICAGO, ILLINOIS.

DYNAMO-ELECTRIC MACHINE.

SPECIFICATION forming part of Letters Patent No. 259,061, dated June 6, 1882.

Application filed December 15, 1881. (No model.)

To all whom it may concern:

Be it known that I, CHAS. J. VAN DEPOELE, of Chicago, in the county of Cook and State of Illinois, have invented an Improvement in 5 Dynamo-Electric Machines, of which the following is a specification.

My invention consists in a new construction of the armature for dynamo-electric machines, and comprises a new mode of constructing, 10 winding, and connecting the armature-coils; also, of new combinations of the various parts constituting my armature, all as fully set forth in the following specification, and specifically pointed out in the claims, reference being had 15 to the annexed drawings, in which—

Figure 1 is a vertical longitudinal section of my armature, showing construction of frame thereof. Fig. 2 is an end view of armature-frame. Fig. 3 is a vertical longitudinal section, showing the connection of two opposite coils. Fig. 4 is one-half of a cross-section, showing connection of coils with commutator. Fig. 20 5 is a similar cross-section, showing connection of coils with the insulated ring. Fig. 6 is a diagram cross-section, showing mode of winding and connecting the wire upon the cores. Fig. 7 shows in an end view the commutator and collecting-brushes. Fig. 8 is a detached perspective view of one of the coils.

30 In the drawings, A is the shaft of the armature, to which are secured the two brass disks B B.

C C are a number of coils arranged cylindrically around the shaft and stepped with 35 their ends into recesses a, formed on the inner sides of the brass disks B B.

D are soft-iron rods, also placed cylindrically around the shaft in the intervals between the coils, with their ends passing out through 40 the disks and provided with screw-nuts f f.

F is a metal ring insulated from the shaft, but firmly secured thereto.

G is a commutator, also secured to the shaft, and divided in sections corresponding to the 45 number of coils in the armature.

H is the top collector; H', the bottom collector.

I and I' are brushes.

The construction of the coils C is as follows: 50 b is the inner core, made of a thin soft-iron plate, bent or doubled upon itself, as repre-

sented in Fig. 1, leaving a central opening, c. The point at which the free ends of the thin iron plate are brought together is immaterial, as it may be upon either side instead of at one 55 end, as shown in the drawings. d d are pole-faces, and consist of thin soft-iron plates secured to each side of the core b by means of rivets e, passing through the opening c of the core. The face-plates d d are perforated and 60 their ends fitted to enter into the recesses a of the disks, as shown. The core b, with the plates d d, thus forms a spool upon which the wire is wound in the following manner: The spool being attached to some suitable machine for winding, one layer of wire is wound upon the core and then a thin plate of soft iron, insulated on 65 both sides, is wrapped around it. Then another layer of wire is wound over it, with another plate of insulated soft iron wrapped on top of 70 it, and so on, one layer of wire alternating with a layer of insulated soft-iron plate until the required amount of wire is wound on, the different layers of wire being formed of the same 75 continuous wire.

It is evident that one or more bent plates or cores can be used in connection with the face-plates d, and one or more layers of wire to form a magnet, without departing from the spirit of my invention.

For mounting the armature the coils are placed vertically upon the inner side of one of the disks B, with the coils stepped into the recess a, between the rods D. Then the other disk, A, is slipped on top and the nuts f f firmly 85 screwed down upon the rods D. The shaft B can now be passed through the disks and the latter secured thereon by means of set-screws. Next, all the inside ends of the wires are connected to the ring F, and all the outside ends 90 of the same are connected to a corresponding section of the commutator G.

Having thus described all the different parts of my armature, I will now proceed to explain its action while revolving in its field of force, 95 where it belongs.

On examining Fig. 7 it will be seen that one half of the sections of the commutator are in connection with the top collector, H, through its brushes I, while the other half of the commutator is in connection with the lower collector, H' through its brushes I'; and if we 100

connect now, for instance, the positive pole of a battery or other source of electricity to the collector H, and the negative pole to the collector H', the current will flow through one half of the coils of the armature in the same direction to the ring F and pass over to the other half of the armature-coils, through which it passes in the same direction, (see Fig. 6,) and is then finally collected by the brushes I' and collector H', and completes its circuit to the negative pole of said battery. In Fig. 6 the positive pole of the armature will then be at P+ and the negative pole at P-, while N and N' mark the neutral points. Now, on revolving the armature in a field of force of ordinary construction and connecting the same properly with the coils of said field, a continuous current is produced.

I am aware that it is not new to construct electro-magnets of alternate layers of wire and iron tubes, or layers of wire and layers of transverse iron rods, and I do not claim such construction. In my invention iron plates are bent to form smooth surfaces on which the wire is wound, and each iron plate fits closely around and forms a perfect binding for the layer of wire beneath it. This construction renders the winding of the magnets very easy compared with that style of magnet in which

numerous transverse iron rods or wires are 30 used.

What I claim is—

1. In an armature, a series of sectional cores, each composed of thin sheet-iron plates, folded upon themselves, in combination with layers 35 of wire wound between said metal plates, substantially as described.

2. In an armature for a dynamo-electric machine, a magnetic section consisting of a sheet-iron core bent or doubled upon itself and secured to pole-faces of the same material and 40 coils of wire wound upon said core, substantially as described.

3. The pole-faces *d*, in combination with the bent sheet-iron cores *b*, forming supports for 45 the layers of wire forming the magnet-coil, substantially as described.

4. The combination, with the pole-faces *d*, having projecting ends, of the alternate bent sheet-iron cores *b* and layers of wires secured 50 between said pole-faces, the disks *B*, having recesses to receive the ends of said pole-faces, the rods *D*, and the nuts *f*, substantially as described.

CHAS. J. VAN DEPOELE.
